UNITED STATES PATENT OFFICE

HENRY T. PREBLE, OF BERKELEY, CALIFORNIA.

MECHANICAL OILER.

1,121,536.

Specification of Letters Patent. Patented Dec. 15, 1914.

Application filed December 27, 1912. Serial No. 738,820.

To all whom it may concern:

Be it known that I, HENRY T. PREBLE, a citizen of the United States, and a resident of the city of Berkeley, State of California, have invented new and useful Improvements in Mechanical Oilers, of which the following is a specification.

This invention relates to improvements in mechanical oilers for engines.

10 The objects of this invention are to provide an oil circulating system for engines, more particularly for internal combustion motors, that is simple, direct and reliable, that will distribute an equal quantity of oil 15 to the several divisions of the crank chamber, and that will give visual evidence of the proper working of the several divisions of the system.

10 The invention possesses other advantageous features that, with the foregoing, will be set forth at length in the following description, wherein I shall outline in full that form of the invention selected for illustration in the drawings accompanying and forming part of the present specification. The novelty of the invention will be included in the claims succeeding said description. From this it is apparent that I do not 25 restrict myself to the disclosure made, by 30 said drawings and description, as I may adopt many variations within the scope of my invention as expressed in said claims.

In the drawings: Figure 1 is an end elevation of the invention applied to an internal combustion motor. The crank case is broken away below the line II--II to disclose the pump in full lines. Fig. 2 is a plan view from above of the lower half of the crank case below the line II--II disclosing the 35 various oil conduits. Fig. 3 is an enlarged detail in front elevation of the conduit manifold. Fig. 4 is a plan view from above of the distributor with the top plate removed. Fig. 5 is a vertical cross section of the same 40 taken on the line V--V. Fig. 6 is a side elevation partly in cross section of the oil pump bracket.

45 In detail the construction consists of the oil reservoir or sump 1 attached to the bottom of the crank case 2. The oil pump 3 is incased in a hollow bracket 4 that is hermetically attached to the crank case. The cored opening 5 leads from the discharge port of the pump and registers with the cored conduit 6 in the wall of the crank case. The pump is preferably of the "gear

type," wherein two enmeshed gears are inclosed in a tight casing. This casing is provided with an inlet port on the approaching side of the gear enmeshment and a discharge port on the receding side of the enmeshment whereby the oil drawn into the casing through the inlet port is discharged through the outlet port. One gear of the pump is driven by the vertical shaft 7 extending through the stuffing box 8 and has the spiral gear 10 fixed thereon, enmeshed with the gear 11 fixed upon the cam shaft 12 of the engine. At high engine speeds the pump handles more oil and vice versa. In this manner the circulation of oil is proportioned to the engine speed.

By submerging the pump in the oil "priming" is constantly maintained. By driving the pump with a vertical shaft extending upward through the crank case, the drive mechanism is simplified, well lubricated, and wear of the parts minimized. The pump includes the inclosing casing 14, surrounded by the depending wall 13, closed at the top. The inlet port opens within the wall and the discharge port passes through this wall and extends upwardly through the bracket 4. The above recited pump mechanisms are cast integral, the bracket having the cored conduit 5. The pump gears are assembled in the inclosing casing and sealed by the cover 15 provided with the stuffing box 8. The attaching flange 16 on the bracket is faced and fits a faced surface on the crank case surrounding the conduit 6 cored in the wall of the crank case. This conduit leads upward and forward to the end of the crank case and is faced to receive the manifold 17 bolted thereto. The conduit 6 registers with the port 18 in the manifold. The oil pumped into the manifold through the port 18 passes upward through the division 19 and the tube 20 and into the feed chamber 21 in the distributor 22.

100 The distributor consists of a box like structure preferably an integral casting. The distributor is divided into compartments 23, 24, 25 and 26; each of these compartments is connected by the passages 27, 28, 29 and 30, terminating at the wall 31 of the chamber 21. The passages 29 and 30 are bridged across to provide for screw holes for attaching the cover 36. This wall is notched at 32, 33, 34 and 35, to permit an overflow of the oil in the chamber 21 into each of said compartments. The notches

are of equal depth to insure an equal distribution of the oil. The top of the distributor is covered by the plate 36 that can be of glass to disclose the condition of each compartment. The bottom of each compartment is provided with the opening 37 through which the oil discharges between the glass plates 38 and 39 on opposite sides of the distributor, to give visual evidence of the oil circulation in each division of the distributor. From each of the upper compartments the oil drops into the lower compartments 40, 41, 42, and 43, respectively connected by the tubes 44, 45, 46 and 47 with the divisions 48, 49, 50 and 51 in the manifold 17. The latter are provided with the outlet ports 52, 53, 54 and 55, having the tubes 56, 57, 58 and 59 screwed therein and respectively terminating in the several divided wells 60, 61, 62 and 63 of the crank case. The crank case is provided with the longitudinal conduit 64 cored therein. The overflow pipes 65 extend upward from the conduit 64 within each oil well of the crank case. Each pipe rises to the predetermined oil level of the crank case. The excess of oil overflows through the pipes 65 into the conduit 64 and returns through the outlet 66 back into the sump.

Having thus described this invention, what is claimed and desired to be secured by Letters Patent is:

1. An oil circulating system comprising a sump, attached to a crank case divided into separate wells, a pump mounted in said sump and geared to the engine shaft, an oil outlet leading from said pump to a manifold, a feed tube connecting said manifold and a distributor, compartments in said distributor fed by a notched overflow wall in said distributor, tubes connecting said compartments with said wells in the crank case, and overflow pipes leading back to the said sump.
2. An oil circulating system comprising a crank case divided into separate wells, a sump connected to said crank case, a pump mounted in said sump, a conduit formed in said crank case leading from the pump to a manifold, a feed tube connecting said manifold with a feed chamber of a distributor divided into compartments, overflow notches in the division wall between said chamber and each of said compartments, tubes leading from said compartments to

said wells, overflow pipes in said wells leading back to said sump.

3. An oil circulating system comprising a crank case divided into separate wells, a sump connected to said crank case, a pump mounted in said sump in a hollow bracket attached to said crank in register with a conduit formed in said crank case, a manifold connected to said conduit and discharging into a distributor having return tubes leading back into the several divisions of the manifold, discharge tubes connecting said manifold divisions with the separate wells of the crank case, and overflow tubes in said wells leading back to said sump. 70

4. An oil circulating system comprising an engine crank case divided into separate wells, overflow pipes in said wells discharging into a sump, a pump mounted in said sump and geared to the engine within the crank case, a conduit leading from said pump to a distributor, having a feed chamber, means for equalizing the discharge from said chamber into separate compartments in the distributor, an opening in each of said compartments discharging past a sight glass into a manifold, divisions in said manifold discharging into the said separate wells. 75

5. An oil circulating system comprising an engine crank case divided into separate wells, overflow pipes in said wells discharging into a sump, a pump mounted in said sump and geared to the engine within the crank case, a conduit cored in the walls of said crank case and leading from said pump to a division in a manifold bolted to the crank case, a tube leading from said division to a feed chamber in a distributor, compartments in the distributor divided from said feed chamber by a wall, notches in said wall between each compartment and the feed chamber, an opening in each of said compartments discharging past a sight glass into a manifold, divisions in said manifold, tubes leading from said divisions to the respective wells in the crank case aforesaid. 95 100

In testimony whereof I have hereunto set my hand at Stockton county of San Joaquin State of California this 20th day of October 1912.

HENRY T. PREBLE.
